FRANCIS JOSEPH FEE, OF NEW YORK, N. Y.

AUTOMATIC SPRINKLER-HEAD.

1,253,019.

Specification of Letters Patent.

Patented Jan. 8, 1918.

Application filed February 21, 1916. Serial No. 79,581.

To all whom it may concern:

Be it known that I, FRANCIS J. FEE, a citizen of the United States, and a resident of the city of New York, borough of Manhattan, in the county and State of New York, have invented a new and Improved Automatic Sprinkler-Head, of which the following is a full, clear, and exact description.

This invention relates to automatic sprinkling devices for buildings and has particular reference to means for reliably initiating the flow of water in the event of sufficient heat being generated in the vicinity of the device to melt an easily fusible metal.

Among the objects of the invention is to improve the means for insuring that the parts normally held from relative separation by the fusible metal shall separate bodily or substantially one from the other at all points when the fusion takes place, whereby a softer and weaker fusible metal may be employed for the purpose than may be used in the ordinary devices now on the market.

Another object of the invention is to improve the tension means for sprinkling heads so as to make available in a superior manner a means whereby the principal tension is sustained by non-fusible metals or by metals of such a nature and form as to resist any tendency of what is known in the art as "cold flow" with a corresponding release of the valve mechanism, prematurely.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a vertical sectional view of a preferred embodiment of the invention with the parts in normal closed or sealing position, the section being on the line 1—1 of Fig. 2;

Fig. 2 is a side elevation of the same looking toward the left in Fig. 1;

Fig. 3 is a view corresponding to Fig. 1 but indicating the releasing action under the influence of heat;

Fig. 4 is a transverse sectional detail on the line 4—4 of Fig. 1 showing particularly the cross-sectional form of the yoke arms:

Fig. 5 is a front elevation of the tension member;

Fig. 6 is a bottom plan view of the spreader; 60

Fig. 7 is a bottom plan view of the cap; and

Fig. 8 is a cross sectional detail of one of the toggle link arms showing the shape providing a point contact with the side edge of 65 the yoke arm whereby the possibility of a sluggish collapsing action due to corrosion, calcimine or the like is avoided.

The general principles and construction of this invention are similar in the main to 70 many devices heretofore proposed and on the market, the same including a body 10 constituting a delivery nozzle and tapped into the water pipe connection 11. Said nozzle is provided with a slightly contracted throat 75 surrounded by a rim or seat 12. This body is provided with flat faces for convenience in manipulation. A yoke comprising upwardly and inwardly curved arms 13 is connected to the body and this yoke provides a 80 support 14 having an axis in alinement with the axis of the nozzle opening, said support being internally threaded for the accommodation of a compression member in the form of a screw 15 acting downwardly 85 toward the nozzle seat 12.

At 16 is indicated the cap for normally closing the nozzle and preventing the escape or leakage of water. This cap comprises preferably two parts; first, a disk 17 of 90 copper, German silver, or some other non-corrodible metal and adapted to make direct intimate contact with the edge or rim 12. The other part of the cap is of brass or some other suitable, strong, rigid material. The 95 two parts 17 and 18 are permanently and rigidly united by any suitable means making practically a single member. Any suitable number or form of projections 19 may be provided on the lower face of the disk 17 100 to prevent lateral displacement of the cap from the nozzle seat. The upper portion of the cap is provided with an upwardly projecting, central, round-pointed post or stud 20. 105

The compression member complete includes not only the screw 15, but also a head or spreader 21 into which the head 22 of the screw is countersunk and locked by means of a key 23. The periphery of the spreader 110 constitutes in effect a downwardly projecting circular rim broken to provide a series

of laterally extending passageways 24 for the water when it shall be thrown forcibly upwardly against the under face of the spreader in practice. The central portion 5 of the spreader constitutes a hub 25 through or from which the threaded portion of the screw projects, and upon the lower face of the spreader are formed a circumferential series of fins 26 extending from the extreme 10 edge of the spreader inwardly tangentially of said hub but of a length stopping short of contact with said hub. I also provide a plurality of vertical holes 27 through the spreader for delivering a portion of the 15 water therethrough. The inner end of the compression member is provided with a central spherical seat for a ball 28.

Between the cap and the compression member I provide a strut comprising two toggle 20 links 29 and 30, one having a spherical cavity at its lower end to receive the point of the stud 20 and the other having a spherical cavity at its upper end to receive the ball 28. The lower link 29 has a concavity 31 to 25 receive the lower edge of the link 30. The concavity 31 and edge of the other link co-operating therewith extend horizontally or at right angles to the line of compression between the center of the ball and the center 30 of the point 20, said line of contact, however, between the toggle links being spaced laterally from the plane coinciding with said line of compression and parallel thereto. In other words, the line of contact between the 35 two links 29 and 30 constitutes in effect a hinge and the toggle members are so arranged that the axis of said hinge shall never come within the aforesaid line of compression. Each of the toggle links or members 40 29 and 30 is provided with an arm 32, each of said arms with the link to which it is connected constituting substantially a right angled bell crank. The outer end of each arm is provided with a hook 33 projecting 45 in the opposite direction from the hook of the other member. Since the longitudinal or compression axes of the links 29 and 30 form an obtuse angle approximating 180 degrees in practice, the two arms projecting 50 laterally from the same side of the device are arranged divergent from each other at their hook-shaped ends, the amount of divergence being proportional to the amount of angularity between the two compression 55 axes of the toggle links. With the toggle links arranged as shown in Fig. 1, and with the compression set up between the ball 28 and the supporting point 20 of the cap, the compression tends to break the toggle at 60 the joint along the line of the hinge aforesaid with a corresponding tendency to increase the divergence of the arms 22 from each other.

One of the principal novel features of this 65 invention lies in the tension member extend-

ing normally between the hooks 33 of the arms and resisting said force of compression tending to break the toggle and increase the divergence of the arms. This tension member is shown in the form of a link 34 comprising a pair of plates 35 and 36 each having a hole 37 therethrough for engagement with one of the hooks 33. Each of these plates is substantially flat except for a depression formed in the central portion of 75 each. The plate 35 is provided with a depression 38 on its inner face, said depression providing a shoulder 39 at its upper end but having its lower end without a shoulder. In other words, this depression in 80 vertical transverse section is substantially wedge-shaped, or in the form of a right angled triangle whose hypotenuse coincides with the inner face of the plate. The other plate 36 is provided with a depression 40 85 having substantially square shoulders 41 and 42 at its top and bottom. These two depressions are so formed as to lie opposite each other when the plates are connected in operative position, or, in other words, with the 90 shoulders 39 and 41 lying in the same or substantially the same horizontal plane. From what has been stated, I would have it plainly understood that each of the plates on its inner face has direct contact against all of 95 that portion of the other plate surrounding said recesses; that is to say, the two recesses communicating with each other so far as the structure of the plates and depressions is concerned form a cavity within the central 100 portion of the link, all of said recesses being remote from all or any exposed edges of both link plates.

Said cavity formed by the recesses of the opposing plates is designed to receive and 105 hold a metal or other strong rigid key 43 practically of wedge shape or of right angled triangular form in vertical cross section, the base of the triangle lying in the bottom of the recess 40 and the right angle 110 of the key fitting into the angle at 41. In other words, the hypotenuse of the triangular key structure extends diagonally across the plane joining the two plates, the key having one edge at one end of said hypotenuse lying in the angle at 42 and the opposite end of the hypotenuse in or against the angle at 39 of the opposite plate. This key, therefore, lies in direct contact with the metal of the plates 35 and 36 and serves under normal conditions to sustain nearly all 120 of the tension applied to the link by the tendency of the toggle devices to spread the arms 32. Since, however, the active edges of the member 43 lie on opposite sides of the 125 plane of the tension, when the plates are free to separate bodily one from the other, the member 43 acts as a rocker tilting around the fulcrum lines constituting the ends of the hypotenuse above described (see Fig. 3). 130

With the rocker 43 in place in the cavity in the central portion of the tension link, and the flat portions of the plates lying flatly against each other, the meeting edges 5 of the two plates are soldered together by a soft solder or fusible metal indicated at 44, said fusible metal extending all the way around said meeting edges, thereby serving two purposes; first, to lock the plates together forming the tension link, and, secondly, the solder thus applied constitutes a seal excluding all moisture from the cavity in which the rocker is housed. It will thus be seen that the rocker and plate parts engaged thereby are always insured against corrosion or other conditions which would tend to cause the rocker to stick and defeat or retard the action of the plates for separation when required.

20 As in other devices previously proposed for this purpose, the toggle mechanism and the tension device serve as a means to lock the cap in closing position under ordinary conditions, sufficient compression being created through the screw to set up a high degree of strain upon the toggle link to instantly collapse the compression and tension devices upon the weakening of the connection between the tension link plates. Even though the pressure of the water within the pipe and nozzle may be enormous, there is no danger of leakage due to the fact that the compression is almost all applied directly upon the cap. A comparatively small proportion of the strain is exerted laterally, however, due to the angularity of the toggle links, but the fraction of the strain thus deflected laterally is again resisted mainly by the direct draft from one link plate to the other through the direct contact with the rocker 43. It will thus be appreciated that finally but a comparatively small amount of the compression originally set up by the compression member requires to be resisted by the solder or fusible metal 44. It is possible, therefore, by this construction to employ a solder having a very low melting point, and yet possessed of ample strength for the purpose. Furthermore, even though the solder employed may have an exceedingly low melting point, there is no likelihood of premature or accidental separation of the plates 35 and 36 due to cold flow or other conditions, since it must be appreciated that the action of the rocker is such that the turning moment thereof around the two contacting fulcrum edges at the corners 42 and 39 is resisted all the way around the rocker cavity and with practically uniform strength. In other words, the action of the rocker as herein set forth insures that the plates may separate bodily or in practically parallel planes at the moment that the separation is initiated and that practically all of 65 the solder must melt at the same time. In other words, until the heat is sufficient to melt practically all of the solder, there can be no separation of the plates. By forming the plates, however, of copper or of some other metal having high conductivity of 70 heat, the melting of all of the solder will be insured promptly when occasion requires. When the solder melts, however, there is practically no resistance to the rolling or rocking of the rocker around its points of 75 support, and the strut or toggle devices collapse immediately, setting the cap free to be thrown from its place and out of the way by the force of the water. The water then dashes forcibly against the under face 80 of the spreader, a portion of which is projected laterally therefrom along the fins 26, the tangential arrangement of which has a tendency to compress the streams of water causing a portion of it to be delivered far- 85

25 27. In this connection, however, I call special attention to the novel shape of the arms 13 of the yoke, the same having knife edges 45 which set up the least possible resistance to the water being thrown laterally from the vertical axis of the device. The form of the cap is such as to reduce the 90 likelihood of collection and retention of moisture or other conditions which would tend to destroy its effectiveness by corrosion or otherwise. It is to be noted also that the link 34 includes two plates of different identity, making it practically impossible for the device to be improperly assembled. 100

30 I claim:

1. The herein described tension member for an automatic sprinkler head, the same comprising a pair of plates having flat portions lying squarely against each other and also having oppositely arranged depressions forming a cavity in the central portion only of the member, a wedge-shaped rocker member housed entirely within said cavity and spaced inwardly from all edges of the plates, said rocker member having its active faces lying on opposite sides of the plane of contact between the flat portions 105 of the plates, and solder extending entirely around and spaced from said cavity and rocker and sealing all the meeting edges of the plates. 110

35 2. The herein described tension member for an automatic sprinkler head, the same comprising a pair of plates having flat portions in direct contact with each other, one of the plates having a depression whose bottom is parallel to the plane of contact between the plates, the other plate also having a depression communicating with the first mentioned depression forming a cavity, a rocker fitted in said cavity and having direct contact with the plates at the ends of 115 120 125 130

said cavity, said rocker being of substantially right angled triangular form in vertical cross section and having its base fitted squarely in the bottom of the first mentioned cavity, and fusible metal serving to normally lock the plates together.

3. The herein described tension device for an automatic sprinkler head, the same comprising a pair of plates each having a depression formed at its middle portion, said depressions being of different vertical cross sectional form but one registering with the other forming a cavity, a rocker having

greater thickness at one end than at the other fitted within said cavity and having parallel fulcrum edges engaging directly with the opposite plates on opposite sides of the plane of connection between the two plates, and fusible metal sealing the meeting edges of the plates entirely around but spaced from said cavity and rocker.

FRANCIS JOSEPH FEE.
